TAKE-UP CLAMP

James F. Fair, New Kensington, Pa.

Application January 25, 1946, Serial No. 643,220

4 Claims. (Cl. 24—134)

1

My invention relates to clamping devices for ropes and the like, particularly to a device which provides for the drawing of a rope taut and for securing it under tension. The invention consists in certain new and useful improvements in the structure of such devices, affording economy in manufacture, and ease and certainty of operation.

The combination take-up and clamping device of the invention will prove useful in manipulating and securing various tie lines, warping ropes, the halyards and shrouds of boats, etc., but it has been particularly developed for use in tightening and securing clotheslines, in which association it will be described herein, with the wider adaptability and utility held in contemplation.

The invention will be understood upon reference to the accompanying drawings, in which:

Fig. 1 is a view in side elevation of a device embodying the invention, showing additionally a support and the end of a clothesline positioned in the device, ready to be drawn taut and secured;

Fig. 2 is a view of the device in top plan; and

Fig. 3 is a view comparable with Fig. 1, showing the device in rope-securing position.

The device of the invention comprises two members 2 and 3, in this case formed of aluminum, but other metals and materials of suitable strength may be employed. The member 2 is a tension-sustaining element which in this case is constructed of a length of rod shaped to provide at one end an eye 2a, by means of which the device is secured to a hook 4 secured in a clothesline post, it being understood that the eye 2a may be supplanted by a device of other form, suitably adapted to engage the particular support or anchorage available. At its opposite end the tension member 2 includes a loop 2b, the distal end portion of which provides a bearing for a pivot pin 5, by means of which the member 3 is eccentrically united to the member 2 for angular movement as will appear.

The member 3 is a clamping element, including two spaced plate-like portions 3a and 3b that straddle the body portion of member 2 to which the member 2 is pivoted, and each of said plate-like portions is bifurcated, that is, formed with a notch 3c, the bottom and side edges of each notch being rounded and smooth so as not to snag a rope engaged thereby when the device is used, as described below. Extending outwardly from the notched portions 3a and 3b is an integral handle portion 3d, and at the base of said handle portion the body of member 3 located between the

2

notched portions provides a stop portion 3e which is adapted to abut upon the intervening looped body portion of the member 2, with the notched portions of the clamping member 3 extended angularly upward from the pivot 5.

Extending from a point 2c located medially of its length the body of the tension member 2 is inclined towards the loop portion 2b, and this inclined portion, 2d, of the member 2 provides a rounded clamping edge for cooperation with the notched portions of clamping member 3. The inclined clamping edge 2d is eccentric with respect to the center 5 of relative angular movement of the two members 2 and 3, and the space interval 10 between such clamping edge and the center 5 of turning decreases in the extent of the clamping edge from the point 2c to the loop portion 2b. It will be understood, therefore, that, when the clamping member 3 is swung clockwise on the pivot from the position in which it is shown in Fig. 1 into the position in which it is shown in Fig. 3, the two notched portions 3a and 3b straddle the clamping edge 2d, and that the further the clockwise swing of the clamping member the closer the inner ends of the notches 3c move toward the top of the inclined clamping edge 2d. This action provides a wedging effect that is extremely effective to secure the end of a rope or clothesline.

In service the otherwise free terminal portion of the clothesline R to be tightened and fastened is inserted in the two notches 3c, with the clamping member in the open position in which it is shown in Figs. 1 and 2, in which the notched portions 3a and 3b are directed upward above the pivot 5. The free end of the clothesline is pulled in the direction of the arrow, the body of the rope sliding through the notches, until the desired degree of tension has been applied to the reach of line extending from the device. It will be noted that the pull thus applied to tighten the line reacts on the edges of the notches, tending to turn the clamping member 3 in counterclockwise direction, but the engagement of the stop portion 3e upon the body of the member 2 prevents the clamping member from turning, and such clamping member remains in the position illustrated in Fig. 1, with the notches 3c directed upward and the side edges of the notches 35 inclined away from the direction of pull, thereby inhibiting any tendency for the line to slip out of the notches.

When the desired tension has been applied to the clothesline, the handle portion 3d is lifted, 40 turning the clamping member 3 in clockwise di-

rection. This is done without relieving the tension on the line. Due to the particular over-center arrangement of the notched portions 3a and 3b with respect to the pivot 5, it takes but little force to lift the handle portion and turn the clamping member 5, even though there be considerable tension on the clothesline. And when the clamping member has been turned through the relatively small angle necessary to bring the inner ends of the notches to just below the pivot, 10 this tension on the line, acting on the edges of the notches, immediately becomes effective to "snap" the clamping member clockwise, bringing the engaged body portion of the rope or line into engagement with the rounded clamping edge 15 2d. The two notched portions of the clamping member, embracing and extending downward on opposite sides of the clamping edge 2d, effect each a wedging of the body of the rope between the inner end of its notch and the clamping edge 20 2d. Thus, there is a double wedging action which is effective to clamp the line.

It will be perceived that the tension applied to the line initially acts to hold the clamping members 3 in open position (Fig. 1), because the notches 3a and 3b that retain the rope are located above the pivot 5. However, when the clamping member is swung into closed position (Fig. 3), and said notches are located below the pivot, the tension of the line, acting on the side edge of one of the notches, is effective to turn the clamping member clockwise until the engaged body of the line is securely wedged upon the clamping edge 2d, and there to maintain or lock it. Due to the particular eccentricity and inclination of the clamping edge 2d, the greater the clockwise turn of the clamping member 3, the more closely the inner ends of the notches 3a and 3b approach the top of the clamping edge, and the more tightly the engaged body of the line is wedged and secured. And manifestly, then, the greater the tension applied to the line, the greater is the force that tends to turn the clamping member 3 clockwise, and the more secure is the wedging or clamping engagement of the line. The forces are self-accommodating, to insure absolute security of the engaged line.

Within the terms of the appended claims various modifications of the self-locking clamping device described may be made without departing from the spirit of the invention.

I claim:

1. A take-up and self-locking clamping device for a horizontally extending rope comprising two clamping members, a pivot uniting the first clamping member to the second clamping member at a point located adjacent to a terminal end of said second member, the second clamping member having a clamping edge extending toward said end and spaced from said pivot, the space interval between said clamping edge and the pivot decreasing as said edge in its extent approaches said pivot, the first clamping member comprising a bifurcated structure having two notches opening

transversely thereof, the bottoms of the notches being located at a greater radial distance from said pivot than said terminal end of the second clamping member, the first clamping member being movable between a position in which the notches extend in rope-receiving position above said pivot slideably to receive a rope to be drawn taut, and a position in which said notches extend downwardly from said pivot to embrace said clamping edge and securely wedge the body of the rope in said notches against said clamping edge, said downwardly extending notches having a rope-engaging edge positioned to react to horizontal tension applied to the engaged rope for increasing the wedging action against said clamping edge in accordance with the magnitude of such tension.

2. The structure of claim 1, said bifurcated member having a stop portion arranged to engage the body of the second clamping member for supporting said bifurcated member in said rope-receiving position.

3. The structure of claim 2, said bifurcated member having a handle extending upwardly when such member is in rope-receiving position.

4. A take-up and self-locking clamping device for a horizontally extending rope comprising a hook member, a bifurcated member having two notches opening transversely thereof, and a pivot uniting the bifurcated member to the tip of said hook member for angular movement relatively thereto, said hook member having a clamping edge extending toward said tip and spaced from said pivot, the space interval between said clamping edge and the pivot decreasing as said edge in its extent approaches said pivot, the bottoms of the notches in said bifurcated member being located at a greater radial distance from said pivot than the extreme end of said tip of the hook member, the bifurcated member being angularly movable between a position in which said notches extend in rope-receiving position above said pivot slideably to receive a rope to be drawn taut, and a position in which said notches extend downwardly from said pivot to embrace said clamping edge and securely wedge the body of a rope in said notches against said clamping edge, said downwardly extending notches having a rope-engaging edge positioned to react to horizontal tension applied to the engaged rope for increasing the wedging action against said clamping edge in accordance with the magnitude of such tension.
